UNITED STATES PATENT OFFICE.

HARRY H. MINTZER, OF PHILADELPHIA, PENNSYLVANIA, ASSIGNOR OF ONE-HALF TO
MARTHA HELEN MILLER, OF PHILADELPHIA, PENNSYLVANIA.

HAT-FASTENER.

No. 859,098.

Specification of Letters Patent.

Patented July 2, 1907.

Application filed December 8, 1906. Serial No. 346,908.

To all whom it may concern:

Be it known that I, HARRY H. MINTZER, a citizen of the United States of America, residing at Philadelphia, in the county of Philadelphia and State of Pennsylvania, have invented new and useful Improvements in Hat-Fasteners, of which the following is a specification.

This invention relates to improvements in hat fasteners designed especially for use in connection with ladies' hats, the object of the invention being to provide fastening devices which form permanent fixtures of the hat and obviate the use of the ordinary hat pins and the objections incident thereto, the construction being such as to secure the hat firmly in position upon the head without mutilating the hat, causing injury to the scalp or deranging the hair.

In the accompanying drawing,—Figure 1 is a bottom plan view of a hat showing the application of the fastening devices thereto. Fig. 2 is a similar view of one of the fastening devices on an enlarged scale. Fig. 3 is a section on the line 3—3 of Fig. 1.

Referring to the drawings, 1 indicates a hat, and 2 its brim, upon the underside of which is arranged a pair of the fastening devices 3, arranged at diametrically opposite sides of the brim, as shown. These fastening devices are alike in construction, and each consists of a metallic bracket plate or strip 4 curved longitudinally to conform to the contour of the brim at its point of junction with the body of the hat and provided at its ends with openings 5 for the passage of suitable fastenings to secure the same to the brim.

Adjustably secured to the bracket plate is a comb 6, composed of metal, celluloid, tortoise shell, or any other suitable material. The intermediate teeth of this comb are of ordinary construction except that the space between the two center teeth communicates at its outer end with a slot 7 formed in the base or back plate 8 of the comb, which space and slot constitute an extended guide passage to permit the comb to have a maximum range of adjustment on a screw 9 extending downwardly from the center of the plate 4, which screw carries a wing nut 10 to bear upon the plate 8 and central teeth and clamp the comb in any position of adjustment to the bracket plate. The end teeth 11 of the comb are also transversely enlarged or widened and provided with longitudinal slots 12 extending into the plate 8 and closed at both ends, said slots forming guides receiving headed pins or studs 13 carried by the bracket plate, whereby the comb is guided for movement in a true path and is securely retained in applied position. A finger piece 14 is formed upon the

central portion of the rear edge of the comb back 8 to adapt the comb to be conveniently adjusted.

It will be observed that the teeth of the combs face inwardly and that the said combs are adjustable horizontally on the brim toward and from the head of the wearer. Hence when the nuts 10 are relaxed the combs may be forced inwardly until the teeth thereof enter the hair at the sides of the head and then fastened from outward movement by tightening the nuts, whereby the hat will be held firmly in position upon the head, the guiding connections between the bracket plates and combs enabling the latter to be adjusted with facility and preventing independent movement of the same upon the hat.

It will be apparent the described construction and arrangement of the fastenings enables them to be adjusted to securely engage the hair without coming in contact with the scalp, and further obviates the necessity of constantly piercing the hat, as is necessary with the ordinary hat pins. It is also apparent that as these fastenings form permanent fixtures of the hat they cannot become displaced or be easily lost.

Having thus described the invention, what is claimed as new, is:—

1. In a hat fastener, a bracket plate, a comb having a guide slot between the center teeth thereof extending into its back plate and having its end teeth formed with longitudinal slots, guide studs on the bracket plate passing through said slots in the end teeth, whereby the comb is slidably connected with the plate, a stem extending through the slot between the center teeth, and means associated with said stem for adjustably securing the comb to the bracket plate.

2. In a hat fastener, a bracket plate provided on opposite sides of its longitudinal center with headed studs, a comb having a guide slot between the center teeth thereof extending into its back plate and having its end teeth formed with longitudinal slots closed at their opposite ends and also extending into the back plate, said slots in the end teeth receiving said guide studs, whereby the comb is slidably mounted on the bracket plate, a screw stem extending through the bracket plate and central guide slot in the comb, and a nut engaging said stem to clamp the comb in adjusted position.

3. In a hat fastener, the combination with a hat, of bracket plates secured to the underside of the brim thereof, guide members upon the ends of the bracket plates; combs slidably engaging said guide members on opposite sides of their longitudinal centers for horizontal sliding movement transversely of the hat, and fastening means disposed centrally between the guiding connections for securing said combs in adjusted position.

In testimony whereof, I affix my signature in presence of two witnesses.

HARRY H. MINTZER.
